UNITED STATES PATENT OFFICE.

EDWARD L. BENSON, OF OMAHA, NEBRASKA.

SIGNAL-BUOY AND LIFTING DEVICE FOR SUNKEN SUBMARINE BOATS.

No. 861,795.

Specification of Letters Patent.

Patented July 30, 1907.

Application filed November 5, 1906. Serial No. 341,985.

To all whom it may concern:

Be it known that I, EDWARD L. BENSON, a citizen of the United States, residing at Omaha, county of Douglas, and State of Nebraska, have invented a certain new and useful Improvement in Signal-Buoys and Lifting Devices for Sunken Submarine Boats, of which the following is a specification, reference being had therein to the accompanying drawings.

It sometimes happens that a submarine boat becomes disabled beneath the surface of the water in such manner that those on board cannot raise it to the surface to signal for help. It is very important in the event of such an accident to have means provided whereby there may be given not only a signal that the boat is sunken and in distress, but also definite information as to where it is located, the boat itself being out of sight beneath the water. A mere sound signal is not sufficiently definite as to location because submarine sounds can be located only with difficulty, if at all. A visible signal is much more easily and quickly discovered and more accurately fixes the location. It is also important that after the location is determined there may be means of communication established between the rescuers and the occupants of the submarine boat; also means for raising the boat and means for supplying fresh air to the imprisoned occupants during the interval before the boat is brought to the surface.

The object of the present invention is to provide an apparatus whereby, first, the occupants of the sunken boat may cause to be displayed above the surface of the water a visible signal of distress which shall also reveal to anyone seeing the signal the location of the boat or the spot beneath which the boat is lying; second, to provide means whereby the rescuers and the occupants of the disabled submarine boat may communicate with each other; third, to furnish fresh air to the imprisoned occupants; and fourth, to lift the submarine boat to the surface of the water.

In carrying out my invention, I provide a signal buoy which is normally carried in a suitable seat on top of the submarine boat near the conning tower and is controlled by mechanism which is operated from within the conning tower to release it when desired. This buoy carries electric lamps of suitable color for signaling. The buoy has attached thereto a line or rope of light weight relative to the cable for hoisting the boat, and of sufficient length to permit the buoy to rise to the surface from any depth to which the submarine boat is at all likely to descend. For convenience of designation, this rope will be referred to as the buoy rope. There is an electric cable which is connected at one end with the said electric lamps and is connected at its other end with a generator in the submarine boat, whereby after the buoy has reached the surface, the lamps may be lighted for use in signaling. Besides the electric light cable, there is another electric cable which

connects to a buzzer in the submarine by which signals are sent from the rescuers to those confined in the boat, while those in the boat can signal to the rescuers by proper flashing of the lights. There is provided a hoisting cable or wire rope, one end of which is connected with the boat, the other end being connected with the said buoy rope. After the buoy has reached the surface, and after communication has been established between the rescuers and the occupants of the submarine, the rescuers may haul in the buoy rope until the upper end of the hoisting cable comes to the surface, and the hoisting cable may then be connected to a capstan or other apparatus on the rescuing boat to raise the submarine to the surface. There is also provided an air tube, one end of which opens into the conning tower or into the compartment occupied by the crew, and the other end is attached to the hoisting cable or buoy rope, and will be lifted to the surface therewith when the rescuers pull on the buoy rope and the upper end of the air tube can then be connected with suitable pumping apparatus for supplying air through the tube to the submarine. There is also provided an emergency block connected with the boat by a short cable of still greater strength than the hoisting cable above mentioned, the said block being intended for use if the first described hoisting cable is not sufficiently strong to stand the strain of lifting the boat, the emergency block being so constructed with engaging projections that a large hawser with a bowline put in it may be let down from the rescuing boat, the bowline slipping along over the smaller cable as a guide and made to engage with said emergency block, power then being applied through said large hawser from the rescuing boat to lift the submarine.

The invention will be fully understood from the following description taken in connection with the accompanying drawings, and the novel features are pointed out and clearly defined in the claims at the close of the specification.

In the drawings,—Figure 1 is a side elevation of a portion of the top of a submarine boat equipped with apparatus embodying my invention, the buoy and cables and lines being stowed away in a tank near the conning tower as it will be when not in operation. Fig. 2 is an enlarged sectional view of the tank in which the buoy and cables are stowed away and of the releasing lever connected therewith from the interior of the conning tower. Fig. 3 is a side elevation showing the buoy floating on the surface of the water after it has been released from the tank and has risen to the surface and before the small line has been drawn up to lift the hoisting cable. Fig. 4 is a side elevation showing the apparatus in the position after the small line has been all hauled up to bring the end of the hoisting cable to the surface and carrying with it also the air hose and showing the emergency cable and block, the top of the

boat being partly broken away to show the buzzer and the generator and electric connections for operating the buzzer and the lights. Fig. 5 is a diagram illustrating the electric apparatus and connections. Fig. 5 is an enlarged detail of the buoy partly in section. Fig. 7 is an enlarged sectional detail showing the lamps and casing therefor and connection with the buoy. Fig. 8 is a detail showing the manner in which the releasing lever is connected with the buoy.

10 Referring now to the drawings,—1 represents the upper portion of a submarine boat equipped with my apparatus, a portion only being shown which is sufficient to illustrate the invention.

15 2 is the conning tower, and 3 is a tank in which the buoy and cables are stowed away for protection to be ready for use when required.

20 The buoy 5 may be of any suitable shape to conform to the requirements of the most adaptable place in which to put it, and is preferably made of cork or sheet steel. The cork buoy, however, is best owing to its lightness in carrying power and owing to the fact also that it is not so liable to be destroyed and sunk when struck by any vessel. If made of cork, it is preferably covered with well tarred canvas 56 to prevent chafe 25 and wear. It is also preferably bound by steel vertical hoops 6 to add to its strength and stability. Through the buoy a steel tube 7 is fitted to be a conduit for a double conductor electric cable 8 leading through it and having branches 81 and 82 which lead to the 30 signal lanterns or lamps 9, 10, respectively, which are secured to the top of the buoy in suitable manner, preferably one above the other. While I have mentioned two lamps or lanterns, the number may be either one, two or more. I have mentioned two, however, because two is in my opinion best for this purpose, one being red and one being white. Preferably these will be 32 candle power electric lamps fitted with red and white shades 11, 12, respectively. These lights may be used to signal with by using the American 35 wigwag or the Morse code in the transmission of signals to the surface. Of course it is understood that any other system may be used if desired. Under the well recognized system of signaling, the upper light will be a red light and the lower light a white light. They 40 are all inclosed in a glass casing 13 so that the light from the lamps may be seen through the casing. A metal partition 14 separates the compartment within which the red light is contained from that in which the white light is contained, so that the lights will not be confused.

45 50 The lamp 10 will be screwed into a suitable socket in this partition plate 14, and the lamp 9 is screwed into a suitable socket in the base 15 of the casing. The casing 13 is secured by bolts 16 to a flange or plate 17 which screws onto the upper end of the steel conduit 55 tube 7. Surrounding the glass casing 13 which incloses the lamps is a wire basket 18 to protect the glass. Below the flange 17 and surrounding the steel tube 7 is a stuffing box 19. The lower end of the steel tube 7 is threaded to receive a flange or plate 20 similar to the 60 flange or plate 17. On the inner face of the flange plate 20 and surrounding the steel tube 7 is a stuffing box 21. This flange plate 20 has secured to its under side two open lugs 22 to receive the fork arms 23 respectively of the releasing bolt 24. While the releasing bolt is shown as formed with fork arms, it is obvious

that a single arm and a single lug would answer the purpose.

Secured to the lower end of the buoy is a line 25 which may be of hemp and preferably as light as may be consistent with sufficient strength to sustain the 70 strain that is required in pulling up the hoisting cable and is the line which as above stated will be referred to as the buoy rope. This line 25 is best secured to the buoy by a bridle 251 which connects with eyes 26 secured to the under side of the flange plate 20. 75

Any suitable means may be provided for retaining the buoy normally on its seat and for releasing the same by operation from within the conning tower. The means shown consists of a forged steel shaft 24 which is forked at its outer end with two arms 23 which pass through the side of the tank 3 and engage with the lugs 22 as already described. In order to properly protect the fork arms 23 from being fouled by the cable when coiled up, there are provided two steel hoods 401, 410, secured to the bottom of the tank 3, one at each end of 85 the lugs 22, said hoods forming additional locking means for the bolt. This shaft passes through a water tight stuffing box 27 in the conning tower 2, and is provided on its inner end with a handle 28 by which it may be readily operated. Outside the conning tower 90 is a helicoid spring 29 surrounding the shaft, one end of which abuts against the wall of the conning tower 2 and the other end of which abuts against a pin 39 which passes through the shaft 24, the spring 29 normally holding the shaft in engagement with the lugs 22 on the 95 flange 20, thereby securely retaining the buoy in the tank.

To release the buoy, a strong pull must be given on the handle 28 of the releasing bolt 24, overcoming the tension of the spring 29 and pulling the arms 23 of the 100 releasing bolt out of the lugs on the buoy. This allows the buoy to rise to the surface with its line 25 and electric cable 8 which connects with the lamps 9 and 10, and the double conductor cable 30, whose lower ends connect with the buzzer 32, the upper ends of cable 30 105 being adapted to actuate the buzzer 32 by an operator from above by bringing the two ends in contact with each other after stripping the insulation from the ends, or by connecting them with any suitable instrument. The upper ends of both leads of cable 30 are well insulated to normally prevent contact with the water and with each other. This line 25 as already described may be made of hemp, a 2 inch line being ordinarily sufficiently large, and probably for practical purposes a length of 150 feet will be sufficient. Secured to the 110 lower end of the line 25 is a wire hoisting cable 33 whose lower end is connected to an emergency block 34 by a common shackle 35 having a swivel bolt 36 which passes through the block 34, the lower end of the bolt 36 being connected by a shackle 37 with the upper end 115 of another wire cable 38, said cable 38 forming a part of the bridle which is secured to the outer part of the submarine. The hoisting cable 33 may be of any size required for the work demanded of it, but for practical purposes, probably a 2 inch type B wire rope will be 120 sufficient and will stand a strain of about 19,000 pounds. The cable 38 should preferably be strong enough to stand a greater breaking strain than cable 33; for instance, a 4 inch wire cable which will stand a breaking strain of about 102,000 pounds. The cable 38 is rela- 130

tively short, say about eight feet probably will be sufficient, its lower end being connected with several slings 40 of heavy wire cable, preferably about the same size as the cable 38, the slings 40 being connected with the 5 hull of the submarine boat in any suitable manner, as for instance, by eye-boats 41 to which the ends of the slings 40 are shackled, and the slings 40 being connected with the cable 38 in any suitable manner. The means shown consists of a large ring 42 which is 10 shackled to the cable 38, and this ring in turn being connected with a number of smaller rings 43 to which the slings 40 are shackled. It is obvious that the size of the cables will be determined by the size and weight of the boat to which the apparatus is fitted.

15 The electric wires 8 and 30 are stopped to the line 25 and to the hoisting cable 33 by rope yarn stops 44 so that the electric cables will be carried with the hoisting cable and rope. An air hose 45 is also stopped to the hoisting cable 33 by stops 46, the upper end of the 20 air hose projecting downward into the submarine through a water tight stuffing box and its upper end being closed with a water tight steel cap 54. This hose should be of sufficient length so that when the upper end of the hoisting cable is drawn to the surface, the 25 upper end of the air hose can be connected with an air pump on the rescuing boat.

The emergency block 34 is provided with arms 47 so that if the circumstances render it desirable to have a hoisting cable of still greater strength than cable 33 30 employed, the people on the rescuing boat may make use of a still larger hawser or cable 48. By forming a bowline in one end and allowing this to slip down over the line 25 and over the hoisting cable 33 until it passes down over the downwardly projecting arms 47 of the 35 emergency block and then by hauling upon the cable 48, the bowline may be made to engage with the arms 47.

In Fig. 5 the electric wiring for both the lamps and the buzzer is diagrammatically shown, 50 representing the dynamo or battery and 51 and 52 representing the 40 keys by which the circuit is made to turn on the lights respectively in lamps 9 and 10.

The operation of the apparatus will be as follows: Supposing the vessel to be in distress when sunken, the operator in the conning tower will pull the handle 28 of 45 the releasing bolt 24, thereby releasing the buoy 5, allowing the buoy to rise to the surface of the water 53, as shown in Fig. 3, it being intended that the line 25 shall be of sufficient length for the buoy to reach the surface without uncoiling any part of the hoisting cable, the 50 hoisting cable being too heavy for the buoy to lift it. When the buoy first comes to the surface, the keys 15 and 52 will be pressed to turn on both the red and the white lights which on the buoy will mean an international signal of a submarine boat in distress. 55 These lights will be left burning and will be a mute call for help from any passing vessel or to the tender of the submarine which shall be near at hand. On the darkest night, this buoy can be distinguished from any other lights by the red and white lights shown together. 60 When these lights are seen by the tender or any other vessel, the proper authorities can be notified at once and the necessary boat sent to the scene. When the rescuers arrive at the scene, the first thing they will do is to pick up the buoy and disconnect the electric ca-

bles from the buoy line and haul in on both, cutting 65 the stops which connect the line and the electric cables as the line and cables come to the surface. The ends of the electric conductors which connect with the buzzer will then be unfastened and the insulation removed from the ends and the wires connected up with 70 a key or just touched together and the necessary signal sent to those below in the submarine telling them that help is at hand and asking for such advice as may be necessary to assure their location and position and thus the occupants of the submarine can give these instructions through different flashing of the electric lights on the buoy by means of the keys in the conning tower in manner well known.

When ready to hoist up the boat, the buoy rope 25 is hauled up until the wire hoisting cable 33 comes in sight. Then this hoisting cable 33 is taken to a capstan or any hoisting device on board the rescuing vessel and a strain put upon it. If the weight of the submarine proves to be too much for the strength of the wire hoisting cable 33, then a large cable 48 with a large hawser 85 should be slipped around the cable 33 and a bowline put in it and allowed to slip down under the projecting arms 47 of the emergency block 34. The upper end of this heavy cable 48 can then be taken to another capstan and by operating both capstans both the cable 33 90 and the cable 48 can be hove in on at the same time. The emergency block will readily take the strain of the cable as the loop 49 of the cable must slip under two or more of the extended arms 47, thus giving a great scope for purchase or as strong a pull as may be needed to lift 95 the submarine. If the submarine is not filled with water, it should not take a very great pull to start her up, and the small cable 33 would be sufficient; but if the boat were filled, the additional hawser lowered under the emergency block would readily lift her. Therefore it is always best to lower the large hawser and get it securely attached to the emergency block before starting to lift. The weight of the complete apparatus required will probably be about 350 pounds but it can be so distributed as not to destroy the buoyancy or stability of the boat. The heaviest part of the apparatus is always attached and evenly distributed over the surface of the submarine and consists of the slings, rings and emergency block.

The tank 3, which contains the buoy, buoy line 25, 110 hoisting cable 33 and electric cables and air hose, will be about $2\frac{1}{2}$ feet in diameter and about $3\frac{1}{2}$ feet high. It will be understood, however, that the dimensions and proportions are not material to the invention. When the buoy is in the tank, the lights will project 115 above the tank and the conning tower and the lights may be used as a night signal system for the submarine when at surface maneuvers or when signaling to battle ships and cruisers. The tank will preferably be made of very light sheet steel as the water pressure will 120 not crush it because the water is on the inside as well as on the outside of the tank, the tank being open at the top. The cables with air hose will be coiled up in the tank ready for running and the buoy will stand on end extending up through the center of the coil, being 125 locked in the manner already described. The only way the buoy can be released at any time is from the inside of the conning tower by pulling the releasing

lever. Preferably the tank is provided with holes 55 in the bottom to allow the water to run out when the submarine comes to the surface.

I claim as my invention:

- 5 1. In combination with a submarine boat, a float buoy, a long flexible connection, one end of which is connected with said float, the other end of which is connected with one end of a second flexible connection of considerable greater hoisting strength than said first mentioned flexible connection, said float having a floating capacity sufficient to lift with it said first flexible connection when the float rises to the surface of the water, said heavier flexible connection having its lower end connected with a short cable of still greater hoisting strength which is also 10 connected with said boat, an emergency block connected with said heavier cable and having hooks projecting therefrom and adapted to be engaged by the loop of an independent hoisting cable which slips down over said previously mentioned hoisting cables.
- 15 2. In combination with a submarine boat, a float buoy, a long flexible connection between said buoy and boat, said buoy and attached flexible connection being adapted to be stowed away on the boat, a signal device on said buoy, a cage on the top of said boat to receive said buoy and flexible connection, an open lug on the bottom of said buoy, a bolt which passes through the side of the conning tower and through the side of said cage and engages with said lug on the under side of the float to normally retain said float within said cage, a handle on said boat whereby 20 the same may be operated from within the conning tower to release the bolt from engagement with said lug and thereby releases the float and a hood which protects said bolt against engagement with the said flexible connections when coiled in said cage.
- 25 3. In combination with a submarine boat, a float buoy, a long flexible connection, one end of which is connected with said buoy and the other end of which is connected with a hoisting cable of considerable greater hoisting capacity than said first mentioned flexible connection, a bridle connection between the lower end of said hoisting cable and said boat, said float having sufficient floating capacity to rise and carry to the surface of the water said first mentioned flexible connection, said flexible connection being adapted to be hauled up from the surface of the 30 water to then lift one end of said hoisting cable to the surface, an electrically operated signal carried by said float buoy, an electric cable connecting said signal with the interior of said boat, means within the boat for operating through said electric cable said electric signal after the float has risen to the surface of the water, a receptacle on the boat within which said float and flexible connections and cables are normally stowed, means for normally holding said float within said receptacle and means whereby said float may be released by an operator from within 35 the interior of the boat.
- 40 4. In combination with a submarine boat, a float buoy, a long buoy line, one end of which is connected with said buoy, the other end of which is connected with one end of a long hoisting cable, said cable being of considerable greater hoisting strength than said buoy line, said buoy having a floating capacity sufficient to lift with it said buoy line when the buoy rises to the surface of the water, an emergency block having a swivel connection with the lower end of said cable, said emergency block having also 45 a swivel connection with a short cable of still greater hoisting strength than said first cable, hooks projecting from said emergency block adapted to be engaged by the loop of an independent hoisting cable, and a bridle connection between the lower end of said heavier hoisting cable and said boat.
- 50 5. In combination with a submarine boat, a float buoy, a long buoy line, one end of which is connected with said buoy, the other end of which is connected with one end of a long hoisting cable, said cable being of considerable greater hoisting strength than said buoy line, said buoy having a floating capacity sufficient to lift with it said buoy line when the buoy rises to the surface of the water, an emergency block having a swivel connection with the lower end of said cable, said emergency block having also 55 a swivel connection with a short cable of still greater hoisting strength than said first cable, hooks projecting from said emergency block adapted to be engaged by the loop of an independent hoisting cable, and a bridle connection between the lower end of said heavier hoisting cable and said boat, said bridle comprising a plurality of 60 cables, each flexibly connected at one end with the lower end of said lowest hoisting cable and spreading apart and flexibly connected at their other ends with the boat.
- 65 6. In combination with a submarine boat, a float buoy, a flexible connection between said buoy and boat, a plurality of electric lamps mounted on said buoy, a casing of transparent material surrounding said lamps and attached to said buoy, and an opaque partition in said casing and dividing it into compartments within which said lamps are respectively mounted.
- 70 7. In combination with a submarine boat, a float buoy, a flexible connection between said buoy and boat, a plurality of electric lamps mounted on said buoy, a casing of transparent material surrounding said lamps and attached to said buoy, and an opaque partition in said casing and dividing it into compartments within which said lamps are respectively mounted and colored shades of translucent material for said lamps differing in color from each other.
- 75 8. In combination with a submarine boat, a float buoy, a long flexible connection between said buoy and boat, a tube extending longitudinally through said buoy, a plate secured to the upper end of said tube, a transparent casing having a base which is secured to said plate, a partition dividing said casing into two compartments one above the other, an electric lamp in the lower compartment secured to a socket in the base of the casing, and an electric lamp mounted in the upper compartment of said casing, electric cables connected with said lamps and passing through the tubular conduit in said buoy and thence to the interior of the boat, an electric generator within said boat and means connected therewith for controlling the lighting and extinguishing of said lamps, and a plate secured to the lower end of said buoy and to said tube, a conning tower, a locking and releasing bolt passing through the side of the conning tower and engaging with lugs on said lower plate on the buoy whereby said buoy may be held on its seat or released therefrom by operation from within the conning tower.
- 80 9. In testimony whereof I affix my signature, in presence of two witnesses.
- EDWARD L. BENSON.
